LESLIE STEVENS, OF GLEN RIDGE, NEW JERSEY.

HAT-SHAPING APPARATUS.

1,258,719.

Specification of Letters Patent. Patented Mar. 12, 1918.

Application filed May 16, 1917. Serial No. 169,072.

To all whom it may concern:

Be it known that I, LESLIE STEVENS, a citizen of the United States, residing at Glen Ridge, in the county of Essex and 5 State of New Jersey, have invented certain new and useful Improvements in Hat-Shaping Apparatus, fully described and represented in the following specification and the accompanying drawings, forming a part of 10 the same.

This invention relates to improvements in apparatus for shaping hats.

In the manufacture of hats it is necessary for a manufacturer to be able to make hats 15 of various shapes in many different sizes.

The variations both in shapes and sizes involve changes both in the shape of the crown and in the shape of the brim and in the dies or shaping devices on which the 20 hats are shaped. In many cases, however, a difference in shape may be only in the crown or only in the brim. The expense involved in providing a complete die for every 25 variation in size and shape of hat to be produced would be very great, and to reduce this expense in equipment two part dies having separate brim and crown shaping portions have been employed, such die parts being 30 formed to be combined in different ways so that each die part could be employed in producing a number of different shapes. Difficulties have been experienced, however, in 35 properly fitting the die parts, especially in fitting them so as to avoid the formation of cracks in the assembled die which would leave marks upon the finished hat, and the employment of two part dies has been accomplished heretofore only by the use of hand-fitted die parts which have to be 40 constructed together and accurately finished with reference to each other so as to make possible a proper assembly.

It is a primary object of the present invention to simplify and improve the construction of hat shaping forms or dies made 45 up of interchangeable die parts, by which the number of shapes produced is increased in proportion to the number of die parts employed. An important feature in the 50 accomplishment of this result resides in the manufacture of all die parts and the die seat in accordance with a specified standard whereby the various interchangeable die

parts made according to this standard will fit accurately together. In this way the necessity for fitting individual die parts to each other is avoided. I accomplish this 55 result of standardization primarily by the selection of certain characteristic determining dimensions or dimensional relations of 60 the die parts, and in some cases also of the supporting devices for the dies, which dimensions and relationships are adhered to in all cases.

Other objects of the invention are to provide sectional dies so constructed that they 65 may be quickly and accurately assembled in proper relationship; to provide die parts which can be accurately fitted together so as to avoid leaving cracks or spaces which 70 will produce marks on the finished hats, and to produce sectional dies in which each part of the die is directly supported upon the die seat or other rigid part during the subjecting of the hat to pressure, whereby the 75 stresses produced are properly taken up and the die parts adequately heated. Other objects of the invention will appear from the following detail description of certain approved embodiments of the invention which 80 I have chosen for purposes of illustration.

In the accompanying drawings which form a part of this specification:—

Figure 1 is a sectional plan view on line 1—1 of Fig. 2, showing a two-part die 85 mounted in a supplementary die seat or bushing;

Fig. 2 is a transverse vertical section on line 2—2 of Fig. 1;

Figs. 3 and 4 are enlarged detail perspective views of portions of the brim die and crown die, respectively, showing the centering pin construction;

Fig. 5 is a vertical sectional view of a modified form of two-part die; and 95

Fig. 6 is a vertical sectional view through the die seat of a press showing the crown die illustrated in Fig. 5 mounted therein but provided with a brim die of modified form from that shown in Fig. 5. 100

For the purpose of illustrating the invention, I have shown the same as embodied in dies of the character commonly employed in hydraulic hat presses of the type in which the hat, after blocking, is laid in a heated 105 metal die and subjected to hydraulic pres-

sure applied to the inside of the hat crown and under surface of the brim by means of a shaped rubber bag fitting the inside of the hat and into and behind which water is forced under high pressure. Presses of this character are well known in the art and my invention finds particular utility as applied to dies for use in such presses, but the invention is not limited to such use and may 10 be employed in connection with hat shaping dies or blocks of any character to which it is applicable.

Referring to the drawings in detail, and particularly to Figs. 1 to 4 inclusive, 1 designates a supplementary die seat or bushing which is adapted to be employed in connection with a conically recessed die seat of the form commonly employed in hydraulic hat presses. Such a die seat is illustrated at 20 in Fig. 6, and comprises a steam chest having a cone shaped recess 3 in the top thereof. The supplementary seat 1 is adapted to be placed in this recess, it being provided with webs 4 having inclined walls 5 adapted to 25 fit the conical wall of the recess 3. The supplementary seat 1 has formed in it a recess 6 adapted to receive a crown die, and around this recess extends a flange 7, having a flat upper surface 8. The bottom of 30 the recess 6 is formed with a flat die supporting surface 9, the surfaces 8 and 9 being accurately formed with a standard measured distance between them. For convenience of manufacture the surface 9 may be formed 35 slightly raised from the surrounding portion of the bottom of the recess, as shown. The crown die 10 fits loosely in the recess 6 and has a true surface 11 adapted to rest on the supporting surface 9. The top of the 40 die is also carefully finished to provide a surface 12 in a plane definitely related to the plane of the surface 11 and parallel thereto and at a standard distance therefrom, so that the die will be of a predetermined height between its surfaces 11 and 12. It is also desirably provided with a narrow 45 flange 13 to extend a little way over the flange 7 but out of contact therewith so that the die is supported entirely by its lower end 50 resting upon the surface 9. The crown die has a suitable shaping recess 14 therein shaped to produce the desired shape of crown.

The brim die part, or brim die, 15, is in 55 the form of a ring formed to fit around the flange portion 13 of the crown die and itself having an inwardly directed horizontal flange 16, the lower surface of which is accurately formed and adapted to fit closely 60 upon the top surface 12 of the crown die. A central opening 17 in this brim die conforms accurately in size and shape with the top of the recess 14 in the crown die, and the upper or outer surface 18 of the brim

die is suitably shaped to produce the desired 65 form of brim. In the construction illustrated, the brim die is provided with a flat upper surface so as to produce a flat brimmed hat. In order to properly locate and support the brim die on the crown die, the outer 70 surface of the flange 13 is most desirably inclined and provided with a plurality of low projecting lugs or "lands" 19, the outer walls of which are adapted to be engaged by the inclined walls 20 of projections or "lands" 21 formed on the brim die. Obviously, the dies could be formed with continuous engaging surfaces if desired, but from a manufacturing point of view it is easier to secure a good fit by utilizing the 80 spaced projections or lands. It is also not essential that the engaging surfaces be inclined, although this is best as it facilitates the placing of the brim die in position and secures a better fit and support of the brim 85 die. The fit of the surfaces 19 and 20 should be such as to permit the flange 16 of the brim die to seat firmly on the top surface 12 of the crown die. The lower surface 22 of the brim die should be accurately formed 90 and spaced a predetermined distance from the lower surface of the flange 16 which contacts with the surface 12, and this spacing should be such that when the flange 16 rests on the surface 12, the crown die being 95 seated on the surface 9 of the supplementary die seat, the under surface 22 will be just out of actual contact with the top surface 8 of the die seat flange 7. This is important as it insures that the flange 16 will rest 100 firmly on the surface 12 and will always be in close contact therewith when the dies are in use, thus preventing the marking of the hat which would result from there being any space at the joint between these parts. At 105 the same time the surface 22 is so close to the surface 8 that when pressure is applied by the upper member of the press a slight springing or yielding of the parts will bring the surface 22 in direct bearing contact with 110 the surface 8 so as to adequately support the brim die and take undue strain off of the crown die. The contact of the surface 22 with the surface 8 is also desirable as increasing the conduction of heat to the brim 115 die. The brim die will thus normally be supported solely by its inner flange 16 resting on the upper end of the crown die, but will under working pressure be additionally supported by its outer portion coming into 120 bearing contact with a supporting surface which in the construction shown in Figs. 1 to 4 and Fig. 6 is provided by the die seat member.

For insuring accurate positioning of the 125 brim die circumferentially with relation to the crown die so as to bring the central opening in the former into accurate regis-

ter with the recess 14 in the latter, a pin and socket construction such as illustrated most clearly in Figs. 3 and 4 is most desirably employed. As shown, one of the lugs 5 21 of the brim die has formed in it an inverted V-shaped socket or recess 23, while in the corresponding land on the crown die a laterally projecting pin 24 is accurately located. The socket 23 has a wide mouth so 10 as to slip readily over the pin and make the assembly of the parts easy, the socket then narrowing down to the width of the pin, thus guiding the parts to proper position while being assembled and finally locating 15 them with the desired accuracy. Preferably the pin is located well up on the land, the socket being of a corresponding depth, as in this way the mouth of the socket may be made relatively quite wide. The ease with 20 which the parts may be assembled is a matter of much practical importance, as in the actual use of dies of this character it is frequently necessary to assemble different die parts dozens or even hundreds of times a 25 day and every second saved in this operation is therefore of importance.

The use of the die seat member having certain fixed or standard dimensions in combination with crown dies and brim dies, 30 having certain correspondingly fixed or standard dimensions, makes possible the ready manufacture of crown dies and brim dies for any desired hat shapes and sizes which may be interchangeably combined. 35 The construction which I have described above I find particularly adapted for this purpose, and with this construction it is possible to secure the desired interchangeability combined with comparative cheap- 40 ness of manufacture. This results largely from the fact that only such dimensions are made standard and only such surfaces are used as reference surfaces as can be most readily finished or machined to accurate size. Thus the supplementary die seat 45 or bushing is provided with but two accurately finished surfaces, namely, the flat parallel surfaces 8 and 9 which may be easily finished true and located a definite standard distance apart. The correct position- 50 ing of the crown die with relation to the supplementary die seat is accomplished by the formation of a single flat surface 11 on the bottom of the crown die which rests 55 upon the surface 9. It is unnecessary to make the side walls of the crown die fit the side walls of the recess in the bushing, and the lower wall of the flange of the crown die is so located as to lie somewhat above 60 the surface 8 so that it need not be finished. The only other parts of the crown die, other than the crown shaping recess itself, which need to be accurately finished and located are the top surface 12 and the surfaces of

the low projections or lands 19. These are 65 the positioning surfaces for the brim die and are located so that the surface 12 shall be a standard predetermined distance from the bottom surface 11, which distance may vary for crowns of different heights. The 70 correct positioning of the brim die is accom- plished by the proper finishing and location of the under surface of the flange 16, which must be adapted to fit upon the sur- 75 face 12 at the top of the crown die, and the surfaces of the inwardly projecting lugs or lands 21 which engage the corresponding surfaces of the lands on the crown die. The lower surface 22 of the brim die is then located at a definite distance from the un- 80 der surface of the flange 16, this dimension depending upon the height of the crown dies with which the brim die is adapted to be utilized, and being always just slightly less than the difference between the height 85 of the crown die and the distance between the surfaces 8 and 9 of the die seat. In this way, as the distance between the surfaces 8 and 9 of the supplementary die seat is a constant, it is possible to secure in all cases 90 the slight amount of clearance desired be- 95 tween the surfaces 22 and 8 before the pres- sure is applied. The proper circumferential registration of the crown and brim dies is secured by the correct location of the pin 95 in the crown die with relation to its notch in the brim die. By forming the fitting surfaces of the various die parts in accord- 100 ance with a known and standard scale of dimensions it is possible to supply a die 105 part at any time which may be fitted accu- rately with die parts previously manufac- tured. Thus it is possible for a hat maker to order new die parts at any time from the die maker with the assurance that they may 110 be employed in connection with the die parts which he already has.

By varying the thickness of the flange 16 on the brim die, which rests upon the top of the crown die and the inner wall 17 of 110 which forms in effect a continuation of the wall of the recess 14, the same crown die may be utilized in producing hats of various heights of crown as well as of different widths and conformation of brim. Fre- 115 quently hats of a certain general style are made with brims of different widths and with crowns different only in height. This may be accomplished by utilizing with the single crown die a number of brim dies of 120 various widths, the thickness of their flanges 16 being proportioned to the width of brim to be produced. A thicker flange 16 has the effect of increasing the depth of the recess 14, thus producing a hat having a 125 higher crown.

Referring to Figs. 5 and 6, I have here illustrated a modification of my invention in

which the supplemental die seat is not employed, the die members being formed to fit directly into the conical recess 3 of the die seat of the press. Fig. 5 shows a crown die 30 shaped to fit the recess 3 and having in it a shaping recess 14 to receive and shape the crown of the hat. The crown die is provided with an upper portion 31 having a tapered outer surface 32 and an accurately 10 formed top surface 12. A positioning pin 33 is also provided projecting from the upper horizontal surface 34 of an outwardly projecting part or flange of the die. 35 is a brim die which has an inwardly projecting flange 16 adapted to extend over and seat on the surface 12 at the top of the crown die, as in the form of the invention previously described. The brim die is made of such thickness that its lower surface 36 clears the 20 surface 34 so as to leave a narrow space between the two, and thus insures that the lower surface of the flange 16 of the brim die shall at all times rest directly upon the surface 12, the space being desirably so 25 small, however, that under operating pressure the outer portions of the brim die will be supported by bearing on the crown die surface 34. The brim die is also provided with a recess into which the pin 33 enters 30 so as to hold the die members in the proper registration. The brim die 35 is shown as provided with a convexly curved outer surface 37 which is adapted to produce a curved brim. 35 In Fig. 6 the crown die 30 is shown as provided with a different brim die 40 which has a flat upper surface 41 adapted to produce a flat brim. The flange 16 of the brim die 40 is also somewhat thicker than the 40 flange of the brim die 35 so that the hat produced will have a slightly higher crown. The brim die 40 is also shown as provided with a conical surface 42 adapted to normally lie just out of contact with the conical 45 surface of the recess 3, the space between these surfaces being so small that when pressure is applied by the upper member of the press the surface 42 will be forced into contact with the surface of the die seat. 50 This direct contact affords direct support for the outer part of the brim die, relieves the strain on the crown die and also assists in the transference of heat from the heated seat directly to the brim die. At the same time 55 the fact that until pressure is applied there is a space between the surface 42 and the die seat, insures that the primary point of support of the brim die shall be upon the surface 12 so that there can be no crack or 60 opening between the flange 16 and the surface 12.

It will be understood that my invention may be practised by other means than those particularly set forth herein and that va-

rious modifications may be resorted to; for 65 example, while the dies are shown as designed to be placed in inverted position on the die seat of a press, it will be understood that they may be otherwise supported or positioned. I, therefore, intend to cover my 70 invention broadly in whatever structural form its principles may be embodied.

What is claimed is:

1. The combination of a crown die having a crown shaping recess therein and 75 formed with a bottom seating face to rest on a flat die seat and an upper seating face, and a brim die formed to seat on the upper seating face of the crown die to be normally supported solely thereby and having an 80 outer seating face at a standardized distance below the face which seats on the crown die to seat on a secondary supporting face under operating pressure.

2. The combination with a crown die having a flange at its upper end, said flange having a plurality of lands projecting beyond the surface thereof, the surfaces of said lands being formed true, of a brim die 90 adapted to fit over said crown die and having surfaces engaging the true surfaces of said lands, and a projection extending laterally from one of said dies interlocking with a recess in the other die for holding said dies in register. 95

3. The combination with a crown die having a positioning projection extending laterally therefrom, of a brim die encircling said crown die, said brim die having a socket formed in its inner face opening inward and 100 downward and adapted to receive said projection for holding said brim die and crown die in circumferential registration.

4. The combination with a crown die having a positioning pin projecting laterally 105 therefrom, of a brim die adapted to encircle said crown die, said brim die having an inverted V-shaped socket formed in its inner face to receive said pin as the brim die is placed on the crown die, the lower end of 110 which socket is substantially wider than the diameter of said pin, whereby when said brim die is placed over said crown die said pin will enter between the walls of said 115 socket and said dies will be brought into and retained in circumferential registration.

5. The combination with a crown die having its upper end formed to serve as a seat for a brim die, of a brim die formed to seat on the crown die and to encircle the upper 120 end thereof, one of said dies having a positioning pin projecting laterally therefrom, and the other of said dies having a V-shaped socket formed in a face thereof to receive said pin, said socket opening in the direction toward the coacting die when the brim die is seated on the crown die and in the direction of the relative approaching move- 125

ment in seating the brim die on the crown die, and the entrance end of said socket being substantially wider than the diameter of said pin, whereby when said brim die is placed over said crown die said pin will enter between the walls of said socket and said dies will be brought into and retained in circumferential registration.

6. A crown die of the character described, 10 having a brim die positioning pin projecting laterally therefrom.

7. A crown die of the character described having an outwardly projecting flange at the top thereof, said flange having a tapered 15 outer wall provided with spaced lands.

8. A brim die of the character described, having a portion adapted to encircle a crown die, said brim die being formed with an inverted V-shaped socket in the inner surface of said portion thereof.

9. The combination of a die seat member, a crown die seated thereon, and a brim die seated on said crown die and normally supported solely thereby and having an outer 25 part normally lying close to but out of contact with the die seat member and adapted to be brought into contact therewith under pressure to additionally support the brim die.

30 10. The combination of a die seat member having a central recess formed at the bottom with a flat supporting surface and having an outwardly extending surface about the top of said recess and parallel to the supporting surface at the bottom of the recess, a crown die mounted in said recess and resting on the bottom thereof, and a brim die comprising an annular body portion surrounding the upper end of the crown die 35 and extending outward over the outwardly extending surface of the die seat member and having an inwardly projecting flange resting on top of the crown die, the difference between the height of the crown die 40 and the distance between the under surfaces of the flange and body part of the brim die being just slightly greater than the distance from the supporting surface at the bottom of the recess to the upper outwardly extending 45 surface of the die seat member.

50 11. The combination with a die seat member having a recess therein having a fixed bottom formed with a flat supporting surface, of a crown die fitting loosely in said recess and located with relation to said seat member by engagement of a flat surface on its lower end with the flat bottom surface of said recess, said crown die having its upper end projecting above the top of said recess 55 in said seat member, the upper surface of said crown die being finished, and a brim die supported on said crown die and located by the engagement of a surface thereof with the upper finished surface of said crown die,

said brim die having a surface normally 65 lying close to but out of contact with a surface of said die seat member and formed to be brought into contact therewith under pressure to additionally support the brim die.

70 12. A crown die having a crown shaping recess therein and having top and bottom finished bearing surfaces and a plurality of finished outwardly facing spaced bearing surfaces for supporting a brim form formed 75 around the outside of the die near the open end thereof.

13. A crown die having a crown shaping recess therein and having top and bottom finished bearing surfaces, a plurality of 80 spaced finished bearing surfaces formed around the outside of the die near the open end thereof, and a positioning member projecting laterally from the die near the same end thereof.

85 14. A brim die comprising an annular body part and an inwardly directed flange, the body part and flange having a continuous upper surface adapted to shape the hat brim, the under surface of said flange 90 and the under surface of said body part being finished as parallel plane surfaces of reference, and the body part of said die having a plurality of inwardly facing spaced inclined bearing surfaces.

95 15. A brim die comprising an annular body part and an inwardly directed flange, the body part and flange having a continuous upper surface adapted to shape the hat brim, the under surface of said flange 100 and the under surface of said body part being finished as parallel plane surfaces of reference, and the body part of said die having a plurality of inwardly facing spaced inclined bearing surfaces and having 105 formed in it an inverted V-shaped positioning notch.

110 16. A brim die comprising an annular body portion and an inwardly directed flange, the upper surface of said body portion and flange being formed to shape a hat brim, the body portion having an inverted V-shaped positioning notch formed in its inner face and extending upward from the bottom edge thereof.

115 17. The combination of a die seat member having two upwardly facing supporting faces in different parallel planes, a crown die having two oppositely facing bearing faces in different parallel planes, and a brim die having two downwardly facing bearing faces in different parallel planes, the crown die being seated on one of the supporting faces of the die seat member, the brim die being supported normally on the upper 120 bearing face of the crown die, and one of the bearing faces of the brim die normally lying close to but out of contact with the upper 125 bearing face of the crown die.

per supporting face of the die seat member, the specified faces of each member being spaced a standardized distance apart to secure interchangeability of such members with others having the same standardized spaced faces.

In testimony whereof I have hereunto set

my hand in the presence of two subscribing witnesses.

LESLIE STEVENS.
